SHINGLE

Herbert Abraham, New York, N. Y., assignor to
The Ruberoid Co., New York, N. Y., a corpora-
tion of New Jersey

Application October 26, 1950, Serial No. 192,254

3 Claims. (Cl. 108—7)

1

This invention relates to a shingle, and more specifically to an improved interlocking T-shaped shingle of the kind commonly known as an asphalt or composition shingle, which shingle is cut from a sheet of felted material saturated and coated with asphaltic or bituminous compositions, and usually faced on the weather surface with mineral granules or particles.

The shingles of the present invention are of the type or class known in the industry as single-coverage shingles. Such shingles are ordinarily used to re-roof old constructions without the necessity of removing the former covering or roofing. When the shingles are applied in interlocked relation they provide a weather and water-proof covering of which a substantial portion is covered with one layer.

There are certain characteristics, in addition to weather and water resistance, that a suitable commercial shingle should have, namely:

(1) From the standpoint of economy they should (a) require the minimum amount of material to cover a "square," or 100 square feet of roof area, with the maximum extent of exposed area; (b) they should be able to cut from sheets of roofing material made from convenient widths of dry felt with a minimum amount of waste; and, (c) the application cost should be low in the number of shingles required to be applied per "square," in the quantity of nails required to affix the shingles, and, moreover, the shingles should be self-aligning so as to avoid the necessity of marking chalk lines on the roof as guides for laying.

(2) From the standpoint of safety the shingles when applied in interlocked relation should: (a) have the maximum resistance to unlocking or disengagement of the locking tab of any shingle from an adjacent shingle due to winds of high velocity, or against having the exposed butts raised unduly by wind pressures; (b) the shingles should provide ample headlap to avoid leakage and to permit the nails that secure the shingles of the next upper course to pass through the underlying shingles; and, (c) the nailing points should be located sufficiently inward from the lateral edges of the overlying shingles to prevent tearing under high wind pressures, also to prevent leakage of water through the nail holes.

(3) The form of the shingles should be such that when laid in interlocked relation the roof covering so formed will have an attractive appearance.

The principal object of the invention is to provide a substantially T-shaped interlocking shingle of the single-coverage type having the fore-

2

ing characteristics and that is extremely economical in respect to the net amount of material required per "square" of roof area. The form and proportions are such that when the shingles are laid to form substantially T-shaped exposure patterns, over half of the entire roof area will be covered with only a single layer of shingle material. The shingle is considerably more economical of material than any comparable shingle of the same type of which I am aware.

Having reference to the accompanying drawings:

Fig. 1 is a plan view of a shingle embodying one form of the invention,

Fig. 2 is a plan view of several of such shingles as applied, in interlocked relation, to a roof,

Fig. 3 is a plan view of a modified form of the shingle,

Fig. 4 is a plan view of several of the shingles of the form of Fig. 3 applied to a roof,

Fig. 5 is a plan view of another modified form of the shingle, and,

Fig. 6 is a plan view of a number of shingles of the modified form of Fig. 5, as laid.

While the several species of the invention differ somewhat in form, one from another, they have the same basic structure, and effect the same economy of material.

Each form of shingle comprises a head portion 10, an intermediate portion 11, a shank portion 12, and locking tabs 13—13 projecting laterally from the butt 14 or lower end of the shank portion of the shingle. In each form the locking tabs each have an inclined upper edge 15, and each shingle at its intermediate portion, has a step or shoulder 16 at each side under which step or shoulder the locking tabs of adjacent shingles are inserted to interlock the shingles. Said steps or shoulders each have a lateral edge 17, which is preferably a straight, vertical line, equal in height to the vertical distance from the butt 14 to the point 24.

An essential feature of the invention is that in each form the width of the shingle is reduced from the head 10 to the shank 12 portion with but a single intermediate step 16.

In each form the head portion 10 may have an extension 18 at its upper end that serves to increase the effective headlap, and permits of passage therethrough of the nails that fasten the shingles of the next upper course, as seen in Figs. 2, 4, and 6 of the drawings.

The proportions of the several portions of the shingle are in general as follows: The head portion 10 (exclusive of extension 18) and the shank portion 12 are each of the same height. The

edges 17 of the intermediate portion 11 are of the same height as the vertical distance from the butt 14 to the point 24 of the tab 13. The overall width of the head portion is three times that of the shank portion, and the width of the intermediate portion 11, between its edges 17-17, is twice the width of the shank, or in other words, the mean of the widths of the head and shank portions.

The sides of the shingles are shaped that when one shingle is inverted relatively to another, the sides of the two will interfit except for the extension 18. This permits of cutting two rows of shingles across a sheet of conventional width with only slight waste along the longitudinal edges occasioned by cutting inward adjacent the butts 14 so that their edges will be free from the coating and granules that normally extend over the edges of the sheet. Since the top edge 19 is concealed when laid it is unnecessary that that edge be free from coating and granules.

Having reference now specifically to the form illustrated in Figs. 1 and 2, it will be seen that side edges 17 of the intermediate portion are each connected at its upper end by a horizontal edge 20 to the corresponding side edge 21 of the head portion, and at its lower end by a horizontal edge 22 to the corresponding side edge 23 of the shank portion. The edges 20 and 22 are of the same lengths, each being one-half the width of the shank 12. With this construction, as will be seen, and as has heretofore been stated, the shingle is reduced from its widest to its narrowest portion in a single step.

When the shingles are laid, as indicated in Fig. 2, the inner angle or crotch 24 of the tabs 13 of one shingle will be interlocked or interengaged with the angle or corner 25 of two adjacent shingles of the next lower course, the shingles being so proportioned as to permit of such interlocking. On reference to the drawings it will be seen that the shingles are self-aligning in that the edges 21 abut the corresponding edges of adjacent shingles, thus facilitating rapid application.

In applying the shingles two nails 26 are driven in each shingle at the position shown to afford the greatest resistance against tearing of the material around the nails. As seen in Figs. 2, 4, and 6, the nails 26 of any one shingle penetrate through the headlap extensions 18 of the two underlying shingles. In this manner, although only two nails are driven into each shingle, as it is applied, the ultimate effect is that each shingle is fastened at four points, two of these points being where the nails are driven into the shingle, and the other two points being where the nails of the shingles of the next upper course penetrate the first mentioned shingle.

The form of shingle shown in Figs. 3 and 4 differs from that of Figs. 1 and 2 in that the edges 17, instead of being connected to the edges 21 and 23 by single horizontal edges, are connected, respectively, by shorter horizontal edges 27-28 and inclined edges 29-30. In this form the distance from the edge 17 to the edge 21, as well as the distance from the edge 17 to the edge 23 (both measured horizontally) is the same, each distance being one-half the width of the shank.

The modified form illustrated in Figs. 5 and 6 has edges 31 and 32, of mutually reversed sigmoid curvature, and of the same lengths, connecting the edges 17 with the edges 21 and 23,

respectively. In this instance also the horizontal distance from 17 to 21, and from 17 to 23, are each equal to one-half the width of the shank.

Shingles of the form and proportions described, when laid as shown, form a roof covering having substantially T-shaped exposure patterns, and of which about 54% of the entire exposed area consists of only a single layer or thickness of shingle material. This effects a marked economy of material and reduction in cost. The saving will be apparent on comparing the present shingle with the one described and claimed in Patent No. 2,050,218, of August 4, 1946, which is also a single-coverage shingle forming T-shaped patterns when laid. With the shingles of said patent the extent of roof surface covered with a single thickness is only about 38.7%, considerably less than half. Furthermore, my improved shingles require a net amount of only about 154 square feet of material per "square" as compared with a net amount of about 173 square feet per "square" of said patented shingle.

The preferred dimensions of the shingle are: over-all width of the head portion, twenty-four inches; width of the intermediate portion, sixteen inches; width of the shank portion, eight inches; over-all height of the shingle, eighteen and one-half inches including the headlap extension 18 of one inch height and the step-edge 17 one and a half inch height.

With shingles of these dimensions, having an eight inch butt exposure, it requires only seventy-five shingles to cover each "square" of roof surface, the exposed area per shingle being about 192 square inches.

I have found that with shingles made of standard asphalt roofing material, of the class weighing about 100 pounds per 100 square feet, the width of the shank 12, particularly of the exposed portion of its butt 14, should not exceed eight inches to avoid the butt from being unduly raised by high wind pressures or velocities to such extent as to cause the locking tabs 13 of any shingle to slip or to be pulled out of locking engagement with adjacent shingles. Where the width is greater, a greater leverage is effected when the butts are raised by wind with the result that the butts tend to unlock and become unlocked, at considerably lower wind pressures. Shingles made of such material having butts of eight inch width, exclusive of the widths of the locking tabs, and having tabs of the form and proportions shown have withstood pressures caused by wind velocities of 110-120 miles per hour, and even higher, without unlocking.

The dimensions stated are illustrative only and may be varied, without, however, varying the proportions, form, and relationship of the several portions of the shingle as herein described.

What I claim is:

1. A single-coverage interlocking shingle of the character described, comprising a head having parallel vertical side portions, a headlap extension on the upper edge of the head, a shank having parallel vertical side portions, said shank having a locking tab at each side of its lower end, and an intermediate step connecting the head and shank, said step having vertical side edges, the width of the head between the parallel vertical side portions thereof being three times the width of the shank between its parallel vertical side portions, the width of the intermediate step being twice the width of the shank, the height of the head exclusive of the headlap extension being the same as that of the shank, and the height of the intermediate step being the

same as that of a locking tab at its vertical line of junction to the lower end of the shank.

2. A shingle as described in claim 1 wherein the vertical side edges of the intermediate step are connected at either side of the shingle by 5 inclined edges each of the same length, with the vertical side edge portion of the head and of the shank, respectively.

3. A shingle as described in claim 1 wherein the vertical side edges of the intermediate step are connected at either side of the shingle by 10 curved edges, each of the same length and curvature, with the vertical side edge portions of the head and the shank respectively, the curved edge connecting the vertical side edge portion of the 15 head and step being reversely curved with respect

to the curved edge connecting the step and the vertical side edge portion of the shank.
